Mass., a corporation of Massachusetts

Application July 19, 1946, Serial No. 684,856

10 Claims. (Cl. 164—68)

1

This invention relates to electrically driven rotary shears, and more particularly to so-called "flying shears" adapted to sever longitudinally moving material into predetermined lengths.

For many years there has been a demand for an electrically driven rotary shear capable of cutting metal billets into accurate lengths as they issue at comparatively high speed from the final stand of the rolling mill, but the inherent difficulties in this situation have heretofore prevented a satisfactory solution. The principal difficulty arises from the necessity for matching the speed of the shear knives with the speed of the billet at the time of the cut, while allowing sufficient range for adjustment in the length of the severed pieces. Unless these speeds are properly synchronized, the cut will not be made in a proper manner and the shear may be seriously damaged. Obviously, if a shear having say a nine foot "shear circumference" or "knife circle" operates at a uniform speed in synchronism with the billet and makes a cut at every revolution, the severed lengths will be nine feet long. Also if such a shear is arranged for mis-cuts so that it cuts every two revolutions or every three revolutions, the severed lengths will be eighteen or twenty-seven feet long respectively. In other words, it is relatively simple to cut lengths which are equal to or multiples of the shear circumference. Ordinarily however the billet must be cut into lengths which are not so directly related to the size of the shear, and it therefore becomes necessary to provide a cyclic variation in the speed of the shear, which presents a difficult problem because of the inertia of the moving parts. It has been proposed to effect this cyclic speed variation by various mechanical means, for example by rocking a differential gearing in the shear drive, but such constructions add to the inertia problems and are very bulky and expensive. It has also been proposed to vary the speed of the electric motor which drives the shear, in a cyclic manner, but no suitable and operative construction of this type has been disclosed heretofore. Further difficulties arise from the fact that the speed of the billet is usually subject to considerable variation, and it therefore becomes necessary to maintain a proper cutting speed for the shear knives and a uniform length for the severed pieces despite such variation in billet speed.

It is accordingly one object of the invention to provide an electrically driven rotary shear which will cut rapidly moving stock into accurate lengths.

It is a further object of the invention to pro-

2

vide an electrically driven rotary shear capable of cutting metal billets as they emerge at relatively high speeds from a rolling mill.

It is a further object of the invention to provide an electrically driven rotary shear which may be readily adjusted to vary the length of the severed pieces while maintaining proper synchronization of the speed of the shear with the speed of the stock as each cut is made.

With these and other objects in view, as will be apparent to those skilled in the art, the invention resides in the combination of parts set forth in the specification and covered by the claims appended hereto.

Referring to the drawings illustrating one embodiment of the invention and in which like reference numerals indicate like parts,

Fig. 1 is a somewhat diagrammatic plan view of a rotary shear and a portion of an associated billet mill;

Fig. 2 is a section taken on the line 2—2 of Fig. 1;

Fig. 3 is an electrical wiring diagram showing one means for driving the shear and controlling the speed thereof;

Fig. 4 is a fragmentary view showing a modification in the diagram of Fig. 3;

Fig. 5 is a graph showing certain relationships of the shear speed to the shear revolutions, obtainable with the arrangement shown in Fig. 3;

Fig. 6 is a graph similar to Fig. 5, showing still further relationships;

Fig. 7 is a graph showing certain relationships of the shear speed to the shear revolutions, obtainable with the arrangement shown in Fig. 4; and

Fig. 8 is a graph similar to Fig. 7, showing still further relationships.

Referring first to Figs. 1 and 2, there is provided a rotary shear 10 arranged to cut a hot metal billet B into predetermined lengths as it emerges from the finishing stand 11 of a continuous billet mill and while a portion of the billet is still between the mill rolls 12. These rolls are

driven by an electric motor 14 which is connected to the rolls by the usual mill pinions (not shown) located within a pinion housing 15, and the usual universal spindles 16. The motor 14 also drives a small pilot generator 17. A suitable roller table 19 supports the billet between the mill stand 11 and the shear 10. A flag 20 is located in the path of the billet to control a normally open switch 21.

The rotary shear 10 may be of any suitable type, and for purposes of illustration I have

shown a shear constructed in accordance with the disclosure of the patent to Morgan et al. No. 2,157,000, granted May 2, 1939. This shear comprises a pair of opposed horizontal crank shafts 23 rotatably supported in a frame 24 and connected to one another by gears 25. These gears are arranged to be driven by four electric motors 21 which are connected to the gears by pinions 28. Each crank-shaft 23 carries a knife head 20 having a knife 31 thereon, and each knife head has a rearwardly extending tail rod 32 with a roller 34 on its end, the roller being guided in a slot 35 in a stationary plate 36. At each revolution of the crank shafts, the knives 31 will meet to sever the billet as it travels longitudinally between them. For purposes of control, as will be explained hereinafter, a limit switch mechanism 37 is connected to the upper crank shaft 23 to be driven thereby.

Referring now to Fig. 3, it will be seen that the fields 39 of the shear motors 21 are connected across a suitable source 40 of constant voltage direct current, under the control of a main switch 41. These motors are provided with the usual mechanical brakes which may be held in the released position by one or more solenoids 42. The armatures of the motors 21 are connected in a circuit with a direct current generator 43, this circuit including a normally open switch 44 under control of the coil 45 of a magnetic contactor. This coil also controls a normally open switch 46 which is connected in series with the solenoid 42 across the source 40. The generator 43 is driven by a motor 47 which is energized from a source 48 of alternating current. The field 50 of the generator 43 is energized by a direct current generator 51 forming a regulating exciter, which is driven by a motor 52, this motor being energized from a source 53 of alternating current. The exciter 51 is preferably of the well-known amplidyne type having, in addition to the usual anti-hunt field and load control fields (not shown), a control field 55 and a reference field 56. This provides a Ward Leonard or adjustable voltage control for the shear motors 21 so arranged that the speed of these motors will be a function of the voltage supplied by the generator 43, this voltage in turn being under the control of the regulating exciter 51. The reference field 56 is more powerful than the control field 55, and these two fields oppose one another.

In order to control the voltage which is supplied by the exciter 51 to the generator field 50, certain control apparatus is provided and will now be described. Thus the pilot generator 17 (which is driven by the mill motor 14 of Fig. 1) has two opposed fields 58 and 59. The field 58 is connected in circuit with one winding of a transformer 60, the other winding of the transformer being connected across the terminals of the generator 43. There are also shown four resistances 62, 63, 64 and 65, and a rectifier 66. A magnetic contactor is provided having a coil 68 controlling two normally open switches 69 and 70, and a normally closed switch 71. A further magnetic contactor is provided having a coil 73 controlling six normally open switches 75, 76, 77, 78, 79 and 80. A further magnetic contactor is provided having a coil 82 controlling a normally closed switch 83 and two normally open switches 84 and 85. A still further magnetic contactor is provided having a coil 87 controlling a normally closed switch 88 and two normally open switches 89 and 90. The limit switch mech-

anism 37 includes three switches 92, 93, and 94 which are controlled by three rotatable cams 95, 96 and 97 respectively arranged to rotate once for each cycle or cut of the shear 10. Thus if the shear makes a cut at each revolution, as in the particular case illustrated, the cams will rotate at the same speed as the shear. If the shear is arranged to make mis-cuts and to cut say every two revolutions or every three revolutions, the cams should rotate at one-half or one third the speed of the shear, respectively.

The electrical connections for the various switches and other devices will now be described. The resistance 63 is connected in series across the terminals of the generator 43. The rectifier 66, the switch 75, the exciter control field 55, and the armature of the pilot generator 17 are connected in a series circuit which in turn is connected across a portion of the resistance 63. The resistance 62 is connected across the switch 75. The switch 76 and the reference field 56 of the exciter 51 are connected in series across the source 40. The resistance 64, the switch 89, and the field 59 of the pilot generator are connected in series across the source 40. This resistance 64 is provided with a slider 100 to form an adjustable rheostat, and the switch 69 is connected across a portion of the resistance by means of this slider. The resistance 65, the switch 88, and the field 59 of the pilot generator are connected in series across the source 40. The flag switch 21 and the coil 68 are connected in series across the source 40. The switch 70 and the coil 73 are connected in series across the source 40. The switch 77, the switch 83, and the coil 73 are connected in series across the source 40. The switch 93 is connected in parallel with the switch 83. The switch 78 is connected in series with the coil 45 across the source 40. The switch 92 is connected in series with the coil 82 across the source 40. The switches 71, 79, and 84, and the coil 82 are connected in series across the source 40. The switches 80 and 85, and the coil 87 are connected in series across the source 40. The switches 90 and 94 are connected in a series circuit which in turn is connected across the switch 85.

It will now be apparent that in the operation of this embodiment of the invention, the switch 41 will be closed, and the generator 43 and the exciter 51 will be driven at substantially constant speeds by their respective motors 47 and 52. The pilot generator 17 will be driven at a speed which bears a definite ratio to the speed of the mill rolls 12 and of the billets B issuing therefrom. As the front end of a billet approaches the flag 20, the switch 44 will be in its open position, and the shear motors 21 will be stationary. The shear 10 will be stationary, with the crank shafts 23 approximately 180 degrees from the cutting position, and the cams 95, 96 and 97 positioned as shown in Fig. 3. As the front end of the bar engages the flag 20, it will close the switch 21 and energize the coil 68 closing the switches 69 and 70, and opening the switch 71. As the switch 70 closes, the coil 73 will be energized, thus closing the switches 75, 76, 77, 78, 79 and 80. As the switches 75 and 76 close, the exciter fields 55 and 56 will be energized, so that the exciter 51 will energize the field 50 of the generator 43. The closed switch 77 will provide a holding circuit for the coil 73. As the switch 78 closes, the coil 45 will be energized, thus closing the switches 42 and 44 and starting the shear motors 21, which will accelerate and bring the speed of the shear knives 31 into synchronism with the speed of the billet before the

knives have reached the cutting position. In the meantime, the front portion of the billet B will have reached a position between the knives, and as the knives come together they will cut a short crop from the front end of the billet.

The shear speed is held equal to the billet speed, during each cut, by the action of the regulating exciter 51 in conjunction with the pilot generator 17. The excitation of the pilot generator field 59 is constant, and determined by the value of the resistance 65. The excitation of the reference field 56 is also constant, whereas that of the control field 55 varies with the speed of the pilot generator 17 and with the voltage output of the shear generator 43. Since the two fields 55 and 56 oppose one another, the latter being the greater, the voltage or output of the regulating exciter 51 is a function of the difference between the excitations of these fields. The voltage produced by the pilot generator 17 and the voltage produced by the shear generator 43 act in opposition to one another in controlling the excitation of the control field 55, and the regulating exciter 51 will vary the excitation of the shear generator 43 to maintain a balanced condition such that the shear speed is equal to the billet speed. Thus, if the billet speed should increase ever so little, the pilot generator 17 would provide a greater voltage, in opposition to the shear generator voltage, thus decreasing the excitation of the control field 55, and causing the regulating exciter to increase the excitation of the field 50, which will increase the voltage produced by the shear generator 43 and increase the speed of the shear motors 27. As the shear reaches billet speed, the voltage produced by the generator 43 will have increased just enough to establish a balanced condition. The function of the rectifier 66 is to block the flow of electricity in one direction, and thereby prevent the control field 55 from being reversed, as might otherwise occur under certain conditions. The purpose of the resistance 62 is to permit a limited flow of current through the control field 55 even with the switch 75 open. The transformer 60 operates only during periods of shear motor acceleration or deceleration, when the voltage applied to the transformer by the shear generator 43 is changing. At such times a current will be induced by the transformer to excite the pilot generator field 58 in such a direction as to oppose the rate of shear motor acceleration or deceleration, as the case may be and thereby prevent the control from over shooting. At other times, the field 58 will remain unexcited.

At the completion of the cut, and preferably immediately after the shear knives have cleared the billet, the cam 95 will close the limit switch 92 momentarily, thereby energizing the coil 82, thus opening the switch 83 and closing the switches 84 and 85. At the same time, cam 97 will close the limit switch 94. Closing the switch 85 will energize the coil 87, thus opening the switch 88 and closing the switches 89 and 90, the latter completing a holding circuit for the coil 87. As the switch 88 opens and the switch 89 closes, the energization of the pilot generator field 59 will be placed under the control of the rheostat 64 rather than the resistance 65, and the shear motors 27 will decelerate or accelerate (as the case may be) to an idling speed which may be either less than or greater than the cutting speed, depending upon the particular lengths which are to be cut from the billet. Thus if the severed lengths required are longer than the circumference of the shear circle, i. e., the orbit of

the centers of the shear cranks, the idling speed must be less than the cutting speed. If the required lengths are less than the shear circle circumference, the idling speed must be greater than the cutting speed. The idling speed, and consequently the lengths of the severed pieces, may be controlled by adjusting the slider 100.

After the shear has operated at its idling speed for a time, and as the knives again approach the billet, the cam 97 will open the limit switch 94 and de-energize the coil 87, thereby closing the switch 88, and opening the switches 89 and 90. This will again place the excitation of the pilot generator field 59 under the control of the resistance 65, and as a result the shear motors will promptly accelerate or decelerate (as the case may be) to synchronous cutting speed. This speed will be attained before the knives engage the billet, and the cut will accordingly be made in a proper manner.

Fig. 5 shows the relationship of the shear speed to the shear revolutions when cutting lengths which require a slowing down of the shear between cuts. As indicated, the shear will travel at bar speed during each cut, and as soon as the knives have cleared the bar the shear will slow down to an idling speed which is determined by the setting of the rheostat 64. At a predetermined point in the revolution of the shear, it will start to accelerate to bar speed in time for the next cut. By varying the idling speed, as indicated for example by the full lines, the dotted lines, and the dot-and-dash lines, the time required to complete each cycle may be varied and the length of the severed pieces may be controlled as desired.

Fig. 6 shows the relationship of the shear speed to the shear revolutions when cutting lengths which require a speeding up of the shear between cuts. In this case the shear will travel at bar speed during each cut, and as soon as the knives have cleared the bar the shear will accelerate to an idling speed which is determined by the setting of the rheostat 64. When the shear reaches a predetermined position it will start to decelerate to bar speed in time for the next cut. The full lines, the dotted lines, and the dot-and-dash lines indicate various idling speeds which may be employed to produce various lengths of severed pieces.

As the tail end of the bar leaves the flag 20, the switch 21 will open, de-energizing the coil 68, opening the switches 69 and 70, and closing the switch 71. Opening the switch 69 will increase the effective resistance of the rheostat 64 and thereby reduce the idling speed of the shear. The coil 73 will remain energized through the switches 77 and 93, despite the opening of the switch 70. As the cam 95 closes the switch 92, and the cam 97 closes the switch 94, the coil 82 will be energized, opening the switch 83, and closing the switches 84 and 85. Closing the switch 85 will energize the coil 87, which will open the switch 88, and close the switches 89 and 90. Closing the switch 89 will place the shear under the control of the resistance 64, which has already been increased an effective amount by the opening of the switch 69, and the shear will immediately decelerate to a very low idling speed. The cam 95 will open the switch 92 shortly after it was closed, but the coil 82 will remain energized through the closed switches 71, 79 and 84. As the shear cranks reach the position shown in the drawings, the cam 96 will open the switch 93 and thereby de-energize the coil 73, opening the

switches 75, 76, 77, 78, 79 and 80. Opening the switch 79 will deenergize the coil 82, thereby closing the switches 83 and opening the switches 84 and 85. Opening the switch 80 will de-energize the coil 87, thereby closing the switch 88 and opening the switches 89 and 90. Opening the switch 78 will de-energize the coil 45 and open the switches 42 and 44, thus disconnecting the shear motors 27 from the generator 43 and de-energizing the brake solenoid 42. The mechanical brakes will thereupon bring the shear to an immediate stop.

With the Ward Leonard system and amplidyne control, as described, very rapid changes in shear motor speed are obtainable, and as a result the shear may be used for cutting billets at high speeds and it may be readily adjusted to cover a wide range of severed lengths. During deceleration of the shear motors, which occurs once for each cut, the speed reduction is effected by means of regenerative braking. In other words, when the voltage produced by the generator 43 is reduced, the shear will drive the motors 27, which will serve as generators, and they in turn will drive the generator 43, which will serve as a motor to drive the motor 47, the latter operating under these conditions as a generator to return electrical energy to the source 48. Such regenerative braking is very effective in producing extremely rapid deceleration, and it results in a considerable saving in power consumption.

It will be noted that in the embodiment illustrated in Fig. 3 the switch 94, which initiates the speed change required to return the shear to bar speed in preparation for each cut, is controlled mechanically by the cam 97. Thus the required speed change always begins at a definite point in the rotation in the shear.

In Fig. 4 there is shown a slight modification in which the cam 97 is omitted, and the switch 94 is controlled by an electronic time delay relay 110 having a rheostat 111 which permits adjustment of the time delay. Operation of this relay is initiated by closure of a normally open switch 112 controlled by the coil 87, the arrangement otherwise being the same as in Fig. 3.

In the operation of the modification shown in Fig. 4, the coil 87 will be energized by the action of the cam 95 (as previously described in connection with the embodiment of Fig. 3) immediately after the knives have cleared the bar, thus closing the switches 89, 90 and 112, and opening the switch 88. This will cause the shear motors to decelerate (or accelerate, as the case may be) toward the idling speed determined by the setting of the rheostat 64. Closing the switch 112 will place the relay 110 in operation, and after a predetermined delay (dependent upon the setting of the rheostat 111) this relay will time out and open the switch 94, de-energizing the coil 87. As in the Fig. 3 arrangement, this will cause the shear motors to accelerate (or decelerate as the case may be) to the cutting speed. Thus the opening of the switch 84, which initiates the speed change required to return the shear to bar speed in preparation for each cut, will take place at a predetermined time after the knives have cleared the bar and the cam 95 has closed the switch 92. By adjusting this time, through the medium of the rheostat 111, the length of the severed pieces may be controlled.

Fig. 7 illustrates diagrammatically the changes in shear speed which take place when the Fig. 4 arrangement is used to cut lengths requiring a slowing down of the shear between cuts. As

indicated by the full lines, the dotted lines, and the dot-and-dash lines, the shear will revolve at bar speed during each cut, decelerate as soon as the knives clear the bar, and accelerate to bar speed at varying times dependent upon the adjustment of the time delay relay 110. If the lengths to be cut are only slightly longer than the circumference of the shear circle, the acceleration may begin before the shear has reached its 10 idling speed.

Fig. 8 similarly shows the speed changes which take place when the lengths to be cut are such as to require a speeding up of the shear between cuts. The lines indicate that the shear will accelerate promptly as the knives clear the bar, and decelerate to the bar speed before the next cut is made, the deceleration starting at varying times dependent upon the adjustment of the time delay relay 110. In the case of lengths which are only 20 slightly shorter than the shear circle circumference, the deceleration will start before the shear has reached its idling speed.

It will now be apparent that the invention provides an electrically driven rotary shear which is capable of cutting very rapidly moving stock into accurate lengths. In particular the invention makes it possible to cut metal billets as they emerge from a rolling mill and while a portion of the billet is still passing through the rolling mill. The arrangement is such that the cuts will be made accurately and in a proper manner despite variations in the delivery speed of the mill.

Having thus described my invention what I claim as new and desire to secure by Letters 35 Patent is:

1. Shearing apparatus comprising a rotary flying shear for cutting longitudinally traveling material, means for feeding material to the shear, an electric motor connected to the shear to drive the same, means to accelerate the motor and to decelerate the motor once for each cutting cycle of the shear, and means effective during such deceleration to cause the motor to operate as an electric generator.
2. Shearing apparatus comprising a rotary flying shear for cutting longitudinally traveling material, means for feeding material to the shear, an electric motor connected to the shear to drive the same, means establishing a cutting speed for the motor corresponding to the speed of the material, means establishing an idling speed for the motor different from the cutting speed, means to change the motor speed from cutting speed to idling speed and vice versa once for each cutting cycle of the shear, one of the speed changes being a deceleration, and means effective during such deceleration to cause the motor to operate as an electric generator.

3. Shearing apparatus comprising a rotary flying shear for cutting longitudinally traveling material, means for feeding material to the shear, an electric motor connected to the shear to drive the same, means establishing a cutting speed for the motor corresponding to the speed of the material, means establishing an idling speed for the motor different from the cutting speed, means operating in timed relation with the shear and effective shortly after completion of each cut to change the motor speed from cutting speed to idling speed, means effective before the next cut to change the motor speed to cutting speed, one of the speed changes being a deceleration, and means effective during such deceleration to cause the motor to operate as an electric generator.

4. Shearing apparatus comprising a rotary fly-

ing shear for cutting longitudinally traveling material, means for feeding material to the shear, an electric motor connected to the shear to drive the same, a main electric generator connected in circuit with the motor and having a field, means to excite the generator field, and means to change the excitation of the generator field and thereby change the speed of the motor twice during each cutting cycle of the shear, one of the changes in excitation causing the generator voltage to be reduced so that the motor will operate as an electric generator and decelerate at a rapid rate.

5. Shearing apparatus comprising a rotary flying shear for cutting longitudinally traveling material, means for feeding material to the shear, an electric motor connected to the shear to drive the same, a main electric generator connected in circuit with the motor and having a field, a regulating exciter connected in circuit with the generator field, the exciter having a control field, means to excite the control field, and means to increase and decrease the excitation of the control field once during each cutting cycle of the shear and in timed relation to the rotation thereof, thereby producing a cyclic variation in the speed of the shear.

6. Shearing apparatus comprising a rotary flying shear for cutting longitudinally traveling material, means for feeding material to the shear, an electric motor connected to the shear to drive the same, a main electric generator connected in circuit with the motor and having a field, a regulating exciter connected in circuit with the generator field, the exciter having a reference field and a control field, means providing a constant excitation for the reference field, means to excite the control field, and means to increase and decrease the excitation of the control field once during each cutting cycle of the shear and in timed relation to the rotation thereof, thereby producing a cyclic variation in the speed of the shear.

7. Shearing apparatus comprising a rotary flying shear for cutting longitudinally traveling material, means for feeding material to the shear, an electric motor connected to the shear to drive the same, a main electric generator connected in circuit with the motor and having a field, a regulating exciter connected in circuit with the generator field, the exciter having a control field, a pilot generator connected in circuit with the control field, the pilot generator having a field, means to drive the pilot generator at a speed bearing a definite ratio to the speed of the material, means to excite the pilot generator field, and means to increase and decrease the excitation of the pilot generator field once during each cutting cycle of the shear and in timed relation to the rotation thereof, thereby producing a cyclic variation in the speed of the shear.

8. Shearing apparatus comprising a rotary flying shear for cutting longitudinally traveling material, means for feeding material to the shear, an electric motor connected to the shear to drive the same, a main electric generator connected in circuit with the motor and having a field, a reg-

ulating exciter connected in circuit with the generator field, the exciter having a control field, a pilot generator having a field, means subjecting the control field to a voltage which is a function of the voltage produced by the main generator and of the voltage produced by the pilot generator, means to drive the pilot generator at a speed bearing a definite ratio to the speed of the material, means to excite the pilot generator field, and means to increase and decrease the excitation of the pilot generator field once during each cutting cycle of the shear and in timed relation to the rotation thereof, thereby producing a cyclic variation in the speed of the shear.

9. Shearing apparatus comprising a rotary flying shear for cutting longitudinally traveling metal bars, a rolling mill arranged to deliver bars to the shear and to control the speed of the bars, an electric motor connected to the shear to drive the same, a main electric generator connected in circuit with the motor and having a field, a regulating exciter connected in circuit with the generator field, the exciter having a control field, a pilot generator having a field, means subjecting the control field to a voltage which is a function of the voltage produced by the main generator and of the voltage produced by the pilot generator, means to drive the pilot generator at a speed bearing a definite ratio to the speed of the rolling mill, means to excite the pilot generator field, and means to increase and decrease the excitation of the pilot generator field once during each cutting cycle of the shear and in timed relation to the rotation thereof, thereby producing a cyclic variation in the speed of the shear.

10. Shearing apparatus comprising a rotary flying shear for cutting longitudinally traveling metal bars, a rolling mill arranged to deliver bars to the shear and to control the speed of the bars, an electric motor connected to the shear to drive the same, a main electric generator connected in circuit with the motor and having a field, a regulating exciter connected in circuit with the generator field, the exciter having a control field, a pilot generator having a field, means subjecting the control field to a voltage which is a function of the voltage produced by the main generator and of the voltage produced by the pilot generator, means to drive the pilot generator at a speed bearing a definite ratio to the speed of the rolling mill, means providing two excitation circuits for the pilot generator field, the first of the excitation circuits being such as to establish a cutting speed for the shear in synchronism with the speed of the bars and the second excitation circuit being such as to establish an idling speed for the shear different from the cutting speed, and means operable in timed relation with the rotation of the shear to render the first excitation circuit effective during each cut and to render the second excitation circuit effective for a portion of the cycle between successive cuts.

EDMUND S. MURRAH.
